UNITED STATES PATENT OFFICE.

EDWARD E. MURPHY, OF CHELSEA, MASSACHUSETTS, ASSIGNOR TO PUFFER MANUFACTURING COMPANY, A CORPORATION OF MAINE.

TUMBLER-WASHER.

SPECIFICATION forming part of Letters Patent No. 723,009, dated March 17, 1903.

Application filed October 9, 1902. Serial No. 126,567. (No model.)

To all whom it may concern:

Be it known that I, EDWARD E. MURPHY, of Chelsea, county of Suffolk, and State of Massachusetts, have invented an Improvement in 5 Tumbler-Washers, of which the following description, in connection with the accompanying drawings, is a specification, like letters on the drawings representing like parts.

The present invention relates to a tumbler-washer of the kind commonly used in connection with soda-fountains and the like, and is embodied in a washer of that type in which the tumbler is placed in a receptacle and acted upon by jets of water controlled by a 15 valve which is commonly actuated by pressing the tumbler into the receptacle.

The main object of the invention is to provide the device with a valve which is easily operated and not affected by the water-pressure, so that it will return readily to its seat 20 when the tumbler is removed without any sudden movement which would result in noise and water-hammer.

The tumbler-washer embodying the invention 25 comprises a receptacle for the water to the action of which the tumbler is subjected, the said receptacle having a suitable drain-outlet and being provided with inlet-jets to distribute the water over the outside and in- 30 side of the tumbler. The inside of the tumbler is subjected to the action of the water passing upward into the inverted tumbler through a middle spray-nozzle, while the outside of the tumbler is washed by water which 35 issues from jets formed in an annular water-tube near the top of the receptacle and pointing diagonally downward. The water is controlled by means of a valve which is adapted to be opened by depressing the tumbler after 40 it has been placed in the receptacle, the said tumbler engaging with and being supported upon a member which constitutes a valve-stem which is longitudinally movable to control the inlet-ports. As herein shown, the 45 said valve-stem is hollow or tubular and provided at its upper end with a nozzle for the water which washes the interior of the tumbler, the said valve-stem having two properly-packed piston members movable in a tubular 50 chamber having lateral inlets between the said pistons. There are two sets of such lat-

eral inlets, both of which sets communicate with the space between the pistons when the valve-stem is in its normal position, so that the pressure is equalized in both directions. 55 The movement of the valve-stem, however, causes one of the pistons to pass beyond one of the said sets of inlets, so that the water entering therefrom passes into the tube beyond the piston and is free to flow out of said 60 tube through lateral outlets leading to the annular spraying device and also through a lateral inlet to the hollow valve-stem in order to supply the spraying device at the end of said stem. With the valve open, however, 65 one of the sets of inlets still admits water to the space between the pistons, so that there is the same pressure tending to maintain the valve open as there is tending to close the same when the tumbler has been removed. 70 The valve-stem is further acted upon by a spring which is of sufficient strength to overcome the friction of the pistons and weight of the valve, so as to restore the valve to normal position when the pressure thereon has 75 been removed, the spring alone, however, acting upon the valve, since the water-pressure is continually equalized, so that the valve will close easily without any thump or shock. 80

Figure 1 is a vertical section through the middle of a tumbler-washer embodying the invention. Fig. 2 is a top plan view of the same; and Fig. 3, a partial vertical section similar to Fig. 1, but showing the valve open 85 instead of closed.

As herein shown, the tumbler-washer embodying the invention comprises a cup-shaped receptacle a of sufficient size to contain the tumbler to be washed, the water being fed to 90 said receptacle through a series of jets b^2 , formed at the end of a hollow stem b , which controls the valve, as will be hereinafter described, and also through a series of pipes c , which lead to an annular pipe c^2 , provided 95 with lateral jets c^3 . The tumbler when applied to the receptacle is inverted and rests upon radial arms or supports b^3 , connected with the stem b , the said supports being symmetrically arranged and provided with coverings, of rubber or similar yielding substance, as indicated at b^4 , to protect the edge 100

of the tumbler when the same is supported thereon. The stem b is depressible and adapted to operate an annular valve, as will be hereinafter described, so that when the tumbler is inverted and placed upon the supports b^3 and then pushed downward the valve is operated to admit water to the interior jets b^2 to act upon the inner surface of the tumbler and also to the jets c^3 , which direct the water in streams against the outer surface of the tumbler. The valve controlled by the stem b is arranged to be balanced under all conditions, so that it is not acted upon by water-pressure, and can be opened or closed independently of the action of such pressure, so that it not only opens easily, but will close without shock. As herein shown, the valve comprises two pistons b^4 and b^5 , each of which is provided with an ordinary cup-leather packing b^6 , the said pistons being connected with the tubular stem b and working in a tubular chamber d , which projects below the receptacle a . The said chamber d is provided with lateral inlets d^2 and d^3 , both of said inlets being between the pistons b^4 and b^5 when the valve is in the normal position. (Shown in Fig. 1.) The space between the two pistons, therefore, is open to the water-pressure, the water being supplied through an inlet e to an annular chamber e^2 , surrounding the chamber d , so that the water passes from the chamber e^2 to the chamber d through the lateral inlets d^2 and d^3 aforesaid between the pistons b^4 and b^5 . The valve-stem b is normally held in the position shown in Fig. 1 by means of a spring b^7 , which is interposed between the lower piston b^5 and the bottom of the tubular chamber d , the strength of the said spring being sufficient to overcome the friction developed between the pistons and the walls of the chamber d and to restore the valve to its normal position after the pressure thereon has been released. As herein shown, the inlet e and the chamber e^2 are formed in a single casting, which is provided with outlet-passages e^3 , leading to a suitable drain-outlet to carry away the water which enters the receptacle a to spray the tumbler. Upon reference to Fig. 1 it will be seen that with the valve in its normal position the water, while free to enter the space between the two pistons b^4 and b^5 , is trapped in said space and cannot escape, it being necessary, therefore, in order to open the valve to move the stem b , carrying the said pistons, until the upper piston b^4 passes the ports d^2 , so that the water is free to flow into the tubular chamber d above the said piston. Upon thus depressing the valve to the position shown in Fig. 3 the water will pass through the ports d^2 to the chamber d above the piston b^4 , and thence through lateral outlet-ports into the tubes c , from whence it issues through the jets c^3 , a portion of the water also passing through the lateral inlet b^8 to the tubular valve-stem b , issuing from said stem, through the jets b^2 in the form of a number of streams,

which act upon the inner surface of the tumbler. At the same time the full pressure of water is admitted through the ports d^3 to the space between the pistons b^4 and b^5 , so that no pressure is exerted upon the valve-stem tending to restore the same to its normal position with the valve closed. Upon removing the tumbler, however, the valve-stem will be moved upward through the action of the spring b^7 , the pressure upon both pistons being equalized in opposite directions as soon as the port d^2 is cut off, so that the water-pressure will not act in any way upon the valve to seat the same, the seating of the valve, therefore, taking place gradually in response to the action of the spring, which need be strong enough only to overcome the weight of the stem and the friction of the pistons.

The main inlet e and the outlet-passages e^3 , as already stated, may conveniently be formed in the same casting, and the tubular chamber d is herein shown as secured by means of screw-threads in a coupling-piece f , which in turn is threaded in a portion of the main casting, as shown. The said coupling-piece f also serves as a support for the tubes c , which are herein shown as three in number, communicating with the lateral outlets f^2 in the coupling-piece f , which is provided with an annular channel just above the member in which the chamber d is formed, there being a valve-seat around the said annular channel which is closed or covered when the valve is in its normal position. The valve-stem b projects through a guide b^9 , screw-threaded in the coupling-piece f , the lower end of which guide constitutes a stop or seat for the valve. The said lower end of the guide is shaped as shown to afford an annular inlet to the ducts c when the valve is open.

For convenience in assembling the chamber d is shown as formed in a tube open at both ends, the lower end being closed by means of a screw-threaded plug d^5 , having a central projection to afford a support for the spring b^7 .

I claim—

1. In a tumbler-washer, the combination with a receptacle; of a movable support for the tumbler provided with a tubular stem and a jet or nozzle; a valve-seat formed around said tubular stem; a cylindrical chamber below said valve-seat provided with two sets of lateral inlets; and pistons on said stem fitting said chamber and so located with relation to said lateral inlets that both sets of inlets normally communicate with the space inclosed between the pistons, one of said pistons traveling past one set of inlets when the valve-stem is moved to open the valve.

2. In a tumbler-washer a hollow movable valve-stem provided with supports for the tumbler; a lateral inlet to said hollow stem; a nozzle at the end of said stem; a chamber in which said stem works provided with lateral inlets communicating with the water-supply; pistons on said stem above and be-

low said inlets, said pistons being so located that one of said inlets communicates with the space between said pistons regardless of the position of the valve-stem; a valve-seat at one end of said chamber coöperating with a valve carried by said valve-stem; and ducts beyond said valve-seat to convey the water to the outside of the tumbler.

3. In a tumbler-washer, a movable hollow valve-stem provided with a lateral inlet and an outlet or nozzle; a chamber having two sets of lateral inlets; pistons on said valve-stem working in said chamber between which pistons said inlets are normally located; ducts 15 at the outlet of the chamber leading to an annular spraying device, one of the pistons being movable past one of the sets of lateral inlets to open communication between the same

and the said ducts; and a spring to hold the valve normally seated.

4. In a tumbler-washer, the valve-stem *b* provided with the pistons *b*⁴ and *b*⁵ and the lateral inlet *b*⁸; the chamber *d* in which said pistons work, provided with the inlets *d*² and *d*³; and the chamber *e*² surrounding the chamber *d* and provided with the inlet-passage *e*, all arranged and located substantially as described.

In testimony whereof I have signed my name to this specification in the presence of 30 two subscribing witnesses.

EDWARD E. MURPHY.
